UNITED STATES PATENT OFFICE

JOHN McG. GILFILLAN, OF TRENTON, NEW JERSEY, ASSIGNOR TO THE TRUMBULL ELECTRIC MANUFACTURING COMPANY, OF PLAINVILLE, CONNECTICUT, A CORPORATION OF CONNECTICUT

DESIGN FOR A COMBINATION HOLDER FOR TUMBLER, BRUSHES, AND COLLAPSIBLE TUBE

Application filed January 5, 1929. Serial No. 29,508. Term of patent 14 years.

To all whom it may concern:

Be it known that I, JOHN McG. GILFILLAN, a citizen of the United States, residing in Trenton, Mercer County, New Jersey, have invented a new, original, and ornamental Design for Combination Holder for Tumbler, Brushes, and Collapsible Tube, of which the following is a specification, reference being had to the accompanying drawing, forming a part thereof.

Fig. 1 is a perspective view of a holder for tumbler, tube and brushes embodying my design.

Fig. 2 is an edge view of the same.

I claim:

The ornamental design for a combination holder for tumbler, brushes, and collapsible tube substantially as shown.

JOHN McG. GILFILLAN.
